POWER UNIT

Stewart B. McLeod, Dearborn, Mich., assignor to
 Detroit Harvester Company, Detroit, Mich., a
 corporation of Michigan

Application December 15, 1950, Serial No. 200,952

16 Claims. (Cl. 268—126)

1

The present invention relates to a power unit and more particularly, to a combination electric motor, hydraulic pump, and hydraulic device combined into a compact self-contained unit.

It is an object of the present invention to provide a power unit of the character described, particularly adapted to serve as an actuator for raising and lowering windows in a vehicle.

It is a further object of the present invention to provide a self-contained electric-hydraulic power unit designed to be self-locking in one direction so as to prevent opening of the window by the application of mechanical force when the pump is not operating, while permitting manual reverse movement.

It is a further object of the present invention to provide an electric-hydraulic power unit including a pump, a piston and cylinder device arranged to have differential fluid inflow and outflow during operation, a fluid reservoir adapted to receive excess flow of fluid or to furnish fluid as required in the operation of the device, check valves controlling flow of fluid into said reservoir, a by-pass around the motor, and means effective to close both check valves upon the application of mechanical force to the power device in a direction tending to cause more outflow of fluid than inflow thereof.

Other objects and features of the invention will become apparent as the description proceeds, especially when taken in conjunction with the accompanying drawings, wherein:

Figure 1 is a fragmentary phantom perspective showing the application of the improved power unit to window lifters.

Figure 2 is a side elevation partly in section of the improved power unit.

Figure 3 is a top plan view of the power unit shown in Figure 2.

Figure 4 is a bottom plan view of the power unit.

Figure 5 is a section on the line 5—5, Figure 3.

Figure 6 is a flow diagram of the system.

Referring now to the drawings, in Figure 1 there is illustrated a portion of an automobile 10 having a door 12 and a body structure 14. In the door 12 there is provided a window 16 adapted to be raised and lowered vertically. Rearwardly of the vehicle there is a window section 18 including a frame 20 which is pivoted as indicated at 22 for rocking movement to open and close the window section 18.

The window 16 is provided with suitable guide means for controlling its vertical movement and is operatively connected to the power unit indi-

2

cated generally at 24, by a lever 26 connected to the piston rod 28 of the power unit, the lever 26 being pivoted at one end to a bracket 30 and having a pin 32 at its other end slidable longitudinally in the slot 34 of bracket 36 carried by the window frame. The power unit 24 is pivotally supported by a bracket 37 suitably secured within the door cavity. The rear window section 18 is moved by a similar power unit 24, the piston rod 28 of the power unit being connected to a lever 38 pivoted to the body of the vehicle as indicated at 40 and having a pin 42 at its other end slidable in a slot 44 provided in the bracket 46 carried by the window. In this case the power unit 24 is pivotally supported on a bracket 47 mounted within the frame of the vehicle below the rear window 18.

In power units controlling the movement of windows of this type it is highly desirable to provide automatically operable locking means which prevent the windows being mechanically opened while the power unit is de-energized. At the same time, it is desirable to include means insuring that dangerous forces will not be applied to the windows in the event that an occupant of the vehicle interposes a hand or other part of his body between the window and the door or body frame. These two requirements are taken care of by the present construction as will subsequently be described.

Referring now to Figures 2—5, the power unit 24 comprises a unitary base 50 in the form of a casting. The base 50 is somewhat elongated and at one end is provided with a recessed cylindrical seat 52 for the reception of an electric motor 54. At the opposite side of the base 50 and at the same end as the motor 54, there is provided a cylindrical recess 56 adapted to receive a pump 57 consisting of an internal gear 58 and an external gear 60. In practice, the internal gear is provided with one more teeth than are provided on the external gear or pinion 60. The pump housing which is formed in part by the cylindrical recess 56 is closed at the lower side by a removable plate 61 secured in place by clamping screw 62. Gear elements 58 and 60 are rotated by the motor and for this purpose the motor shaft 63 extends through an opening provided through the base 50 from the motor seat 52 to the recess 56.

At the opposite end of the base 50 there is provided a cylinder seat 64 surrounded by an annular seating flange 66. The cylinder seat 64 and flange 66 together serve as a closure for the otherwise open end of the power cylinder 68 and

also serve to mount the cylinder in operative position. Outwardly of the annular flange 66 is a cylindrical groove 70 in which is received a ring 72 bolted or otherwise secured in place as by the bolts 74. As indicated in Figure 2, the lower end of the cylinder 68 includes an outwardly extending radial flange 76 engaged beneath the clamping ring 72 and of course, suitable sealing means are provided.

At the same end of the base 50 and at the side thereof opposite to the cylinder 68, there is provided a pivot support 78 having a transverse opening 80 therethrough and strengthened by supporting webs 82. It will be observed that the axis of the opening 80 is perpendicular to and intersects the axis of the cylinder 68, so that the power unit as an assembly will in use rock about an axis intersecting the axis of the cylinder. Located within the cylinder 68 is a piston 84 provided with a piston rod 28 which extends through the cylinder head 88 at the upper end of the cylinder.

Formed within the body of the base 50 and in communication with the bottom of the recess 56 are a pair of ports 90 and 92 in communication with opposite sides of the pump. The pump is designed to be run in opposite direction resulting in a reverse flow of fluid therethrough and for this purpose the motor 54 is also reversible. In communication with the port 90 and within the body of the base 50 is a flow passage 94 which is closed at its outer end by a plug 96. Communicating with the passage 94 is another passage 98 which as best seen in Figure 2, extends through the cylinder seat 64 and thus affords communication between the lower end of the cylinder 68 and the pump port 90. A second longitudinally extending passage 100 is provided within the body of the base 50 and extends to one end thereof where it receives a fitting 102. The head 88 of the cylinder 68 carries a second fitting 104 and the fittings are interconnected by a metal tube or conduit 106, thus affording communication between the upper end of the cylinder and the valve port 92.

Inasmuch as the power unit operates to raise and lower the windows of a vehicle, it is essential to insure that sufficient force is not exerted on the window to cause injury to an occupant who catches his hand or other part of his body between the window and the frame of the door or vehicle. It is also desirable to permit the motor to run after full stroke of the piston. In the present case this is taken care of by providing a small amount of clearance indicated at 107 in Figure 2, and indicated diagrammatically in Figure 6, between one or both of the gear elements 58, 60 and the closure plate 61. Thus, if the motor continues to run when the piston rod 28 is mechanically held against movement, there will be a circulation of fluid within the pump between the ports 90 and 92. This flow is insufficient to seriously decrease the efficiency of the pump in normal operation, but is sufficient to limit the force with which the piston rod 28 is urged upwardly.

Obviously, instead of relying upon a constant amount of clearance between opposite end walls of the pump chamber and the rotating pump elements, a movable end plate could be provided in contact with one side of the pump elements but provided with yieldable means so that upon attainment of sufficient pressure at the discharge side of the pump the plate could yield to permit a by-pass flow within the pump.

Inasmuch as the piston rod 28 occupies the

portion of the cylinder 68 above the piston 84, whereas no similar element is present in the portion of the cylinder beneath the piston, it will be apparent that a differential flow of hydraulic fluid to and from the cylinder 68 takes place upon movement of the piston 84. Thus, when the piston 84 is moved upwardly by a flow of hydraulic fluid under pressure into the lower end of the cylinder, more fluid will flow into the lower end of the cylinder than is displaced from the upper end of the cylinder by movement of the piston therein. Conversely, as the piston moves downwardly there is a greater flow of hydraulic fluid out of the lower end of the cylinder than inflow of fluid into the upper end of the cylinder.

This differential flow requires a reservoir to accommodate the excess flow out of the cylinder upon movement of the piston in one direction and to supply the excess fluid required to move the cylinder in the opposite direction. In the present case the reservoir is provided in the form of a cavity 110 within the base 50. As best seen in Figure 3, where the outline of the cavity 110 appears in dotted lines, it will be observed that the reservoir is of a minimum width on the center line connecting the axis of the motor and the axis of the cylinder. At this point the width of the reservoir is determined by the space between the screw receiving bosses 111 which are also seen in Figure 5. At either side of this center line it is enlarged longitudinally of the base 50. The width of the reservoir on the adjacent center line appears directly in Figure 2 of the drawing. The reservoir 110 is completed by a removable cover plate 112 provided with one or more removable filling plugs 114.

As best seen in Figure 5, the hydraulic fluid flow passages 94 and 109 are interconnected by a transverse passage 116 which terminates at its outer ends in two enlarged valve chambers 118 and 120, the juncture between the transverse passage 116 and the chambers 118 and 120 constituting valve seats 122 and 124 respectively. It will be observed that flow passages 94 and 100 connect directly with the enlarged valve chambers 118 and 120. Outer ends of the valve chambers 118 and 120 are closed by removable plugs 126 and 128 respectively. A passage 130 connects an intermediate portion of the transverse passage 116 with the reservoir 110.

Located within valve chambers 118 and 120 are ball valves 132 and 134 respectively, and intermediate the ball valves is a compression spring 136. The plugs 126 and 128 each include inwardly extending portions 138 adapted to limit outward movement of the adjacent ball valve away from its seat. To accomplish the results desired in a window lift unit, plug 126 is arranged to permit valve 132 to move a relatively great distance from its seat, while valve 134 is closely spaced from its seat.

The operation of the hydraulic system as previously described, depends in part upon the selection of the spring 136 so as to control the flow of fluid in a predetermined manner.

With the parts in the position illustrated in Figures 2 and 6, which corresponds to a lowered or open position of the window, if it is desired to raise the window the motor 54 is energized in the proper direction thus rotating the pump 57 in the direction to pump hydraulic fluid through the port 90, passages 94 and 98, into the bottom of the cylinder 68. This results in upward movement of the piston 84. In the present

construction the entire hydraulic system exclusive of the reservoir remains completely filled with hydraulic fluid at all times so that response is instantaneous in either direction. Accordingly, as the piston 84 moves upwardly fluid is expelled from the upper end of the cylinder but in a quantity less than the inflow of fluid into the bottom of the cylinder. Hydraulic fluid flows out through the fitting 104, the conduit 106, the fitting 102, and the flow passage 100, back to the pump port 92 and to the inlet side of the pump. However, since more fluid is required to move the piston upwardly than is returned through the return line, excess hydraulic fluid is required to be supplied from the reservoir 110. This fluid is supplied through the passage 130, the transverse passage 116 and past the ball valve 134 into the suction flow line 100, and thence to the pump. Operation of the pump establishes a relatively high pressure in the passage 94 and this pressure, acting on the ball valve 132, closes this valve and prevents fluid being forced into the reservoir from the pressure side of the system.

If the piston 84 is in upper position and it is desired to lower the same by power, the direction of rotation of the motor 54 and the pump is reversed, with the result that the passage 100 becomes the pressure flow passage and fluid flows from this passage through the fitting 102, conduit 106, fitting 104 into the upper end of the cylinder. Pressure in the passage 100, and hence in the valve chamber 120, closes the valve 134 and prevents fluid from the pressure side of the system being forced into the reservoir 110. Downward movement of the piston 84 expels hydraulic fluid through the passages 98 and 94 to the pump inlet port 90. However, since more fluid is expelled from the pump than is being delivered to the pump, there is an excess of fluid in the return or suction side of the system. Since the valve 132 is widely separated from its seat, and since pressure in suction line 94 is much less than in the pressure side of the system, valve 132 remains open, and flow of this excess fluid past the valve 132 is permitted. For this purpose the effectiveness of the spring 136 is such that in conjunction with the spacing of the valve from its seat, the spring holds the valve 132 off its seat when the pump is running in a direction such that the passage 94 is at the suction or inlet side of the pump while permitting it to close under manual operation, as will subsequently be described. Thus, the excess fluid expelled from the cylinder 68 is caused to flow into the reservoir 110 during downward movement of the piston 84.

If the motor is stopped with the piston 84 in its uppermost position corresponding to closed position of the windows, the hydraulic system operates to provide an effective lock which will prevent unauthorized entry into the vehicle by forcing the window downwardly. With the piston 84 at the top or upper position of the cylinder 68 and with the pump inoperative, if a force is applied to the window tending to move the piston 84 downwardly, the first effect is to cause a flow of fluid through the passages 98 and 94 to the pump port 90. Since the pump is idle, flow therethrough is restricted and pressure builds up instantly in passage 94 and chamber 118.

The pressure built up in passage 94 and valve chamber 118 is inherently greater than the pressure at this side of the system when the piston is moving down under power operation, with the

pump operating. This is due to a combination of several factors. When the pump is operating in a direction to cause the piston to move downwardly, work is being done and power consumed to accomplish this movement, so that the pressure built up below the piston has to be very substantially less than the pressure above the piston doing the work. Moreover, the effective areas at opposite sides of the piston operate to increase the pressure differential. In addition, the inlet side of the pump is tending to create a suction in line 94. All of these factors combine to insure that under power operation, flow into the reservoir past valve 132 takes place under relatively low pressure. However, when forces are applied to the window with the pump not operating, the leverage of the window operating system provides a large mechanical advantage. Moreover, the window movement is initially opposed by static friction, and when this is overcome, it moves suddenly and creates a surge of pressure below the piston. This results in closure of valve 132. Flow through the by-pass in the pump causes valve 134, with its relatively small clearance, to close at once, and a solid hydraulic block is established.

On the other hand, when the pump is not operating, the windows may be raised manually without difficulty, and will remain locked by the hydraulic block in upper position. In this case, upward movement of the piston will close valve 134, but the by-pass flow through the pump will not close valve 132 to create the hydraulic block. This is for the reason that the excess flow required to fill the cylinder beneath the piston creates negative pressure in line 94, thus opening valve 132 and permitting fluid to flow out of the reservoir 110 into line 94.

The foregoing operation depends in part upon the effectiveness of the spring 136 but is also affected by the location of the inner end of the projecting portions 138 of the plugs 126 and 128. Accordingly, operation of the system is variable by adjustment of the plugs 126 and 128.

Briefly reviewed, when the pump is operating the ball valve at the pressure side of the pump is closed and the ball valve at the suction side of the pump remains open, whether the flow past the ball valve is into or out of the reservoir. However, when the pump is idle, mechanical forces tending to move the piston 84 downwardly result in the development of forces which close both of the ball valves. Since the entire hydraulic system is completely filled at all times, closure of both of the ball valves blocks further movement of the piston. On the other hand, mechanical forces applied upwardly to the piston are effective to raise the piston. This results in closure of the valve 134 but the by-pass flow of fluid through the pump permits the piston to move upwardly. The excess fluid required to fill the cylinder below the piston produces a negative pressure in passage 94 and the fluid flows out of the reservoir 110 into the passage 94.

The drawings and the foregoing specification constitute a description of the improved power unit in such full, clear, concise and exact terms as to enable any person skilled in the art to practice the invention, the scope of which is indicated by the appended claims.

What I claim as my invention is:

1. In a motor vehicle, in combination, a frame part having opposed walls defining a restricted space, an opening through said walls, a window

movable from a closed position within said opening to an open position within said space, a power unit within said space for raising and lowering said window, said power unit comprising a unitary base, an electric motor on said base, a pump recess in said base, a pump in said recess, drive means connecting said pump and motor, a piston and cylinder device on said base, passages at least partly located in said base connecting said pump and cylinder, and window operating means connecting the piston of said device to said window.

2. The combination defined in claim 1 in which said base includes an enlarged cavity therein constituting a fluid reservoir, and passages in said base connecting said reservoir and said pump.

3. Power mechanism for raising and lowering windows and for preventing opening of the windows by the application of force directly to the window which comprises a cylinder, a piston in said cylinder, a piston rod connected to said piston and extending outwardly from one end thereof, said piston rod having means on its outer end for connection to window operating mechanism in such relation that movement of the rod out of the cylinder results in closing of the window, a reversible hydraulic pump, means for providing a restricted flow of fluid between opposite sides of said pump when said pump is idle, flow passages connecting opposite sides of said pump to opposite ends of said cylinder, a reservoir, feed passages connecting said reservoir to said flow passages, check valves in said feed passages, resilient means normally biasing both of said valves to open position and constructed and arranged to permit simultaneous closure of both of said valves in response to a pressure in said flow passages developed by the application of an opening force to the window with the pump stopped, but to remain open in the suction flow passage when said pump is running.

4. Mechanism as defined in claim 3 in which portions of said feed passages are aligned, said valve seats face outwardly of the aligned portions, and the resilient means comprises a single compression spring engaging at its opposite ends the inner portions of said valves.

5. Mechanism as defined in claim 4 in which the check valve in the side of the system connected to the end of the cylinder remote from the piston rod is arranged to close only under higher pressure than said other check valve.

6. A self-locking power unit comprising a reversible pump, a cylinder, a piston in said cylinder, a piston rod on said piston, fluid flow passages connecting opposite sides of said pump to opposite ends of said cylinder, means providing for a restricted flow of fluid between opposite sides of said pump, a fluid reservoir, feed passages connecting said reservoir to each of said flow passages, check valves in said feed passages resilient means normally holding both of said check valves open but providing for simultaneous closure thereof, said valves including means constructed and arranged to provide for closure of said valves at different pressures.

7. A unit as defined in claim 6 in which the resilient means and valves are constructed and arranged to permit closure of the check valve at the pressure side of the pump and to keep the valve open at the suction side thereof when the pump is operating, and to permit closure of both valves when fluid is displaced from the cylinder at the side opposite to the piston rod by

the application of forces directly between said piston and cylinder when the pump is idle.

8. A unit as defined in claim 7 in which portions of said feed passages are in alignment and direct communication with each other, valve seats are provided at opposite ends of said aligned portions, said check valves are disposed outwardly of said seats, said feed passages include a common branch intermediate said seats and connected to said reservoir and said resilient means comprises a compression spring interposed directly between said valves and located in said aligned portions of the feed passages.

9. A power unit for raising and lowering vehicle windows comprising a unitary base, a recess in said base, a pump in said recess, a cylinder support on said base, a power cylinder having one end supported and closed by said support, a first flow passage in said base connecting one side of said pump with the supported end of said cylinder, a second flow passage connecting the other side of said pump with the other end of said piston, a portion of said second flow passage being located within said base, a cavity within said base forming a fluid reservoir therein, a connecting passage in said base extending transversely of said flow passages and terminating in enlarged valve chambers in communication with said flow passages, valve seats at the junction between the ends of said transverse passage and said chambers, valves in said chambers, a passage connecting said reservoir to said transverse passage intermediate said valve seats resilient means normally holding both of said valves off their seats but yieldable to permit closure of one or both of said valves upon establishment of a predetermined pressure in said valve chambers, means providing for a restricted flow of fluid between opposite sides of said pump, a piston in said cylinder, a rod connected to said piston, said resilient means being of such strength as to be yieldable under pump pressure to permit closure of the valve in the chamber connected to the pressure side of said pump but to maintain the other valve open when the pump is operating, and to be yieldable to permit closure of both of said valves when mechanical force is applied tending to move the piston in the cylinder in a direction away from the piston rod.

10. Structure as defined in claim 9 in which said resilient means is a compression spring interposed directly between said valves.

11. Structure as defined in claim 10 in which said valves are balls.

12. Structure as defined in claim 9 in which means providing for a restricted flow of fluid between opposite sides of said pump comprises means providing clearance between parts of said pump.

13. A self-locking power unit comprising a hydraulic device having a differential input and output flow, a reversible pump for supplying fluid to said device, passages connecting opposite sides of said pump to opposite sides of said device, a fluid reservoir in communication with both of said passages, check valves controlling flow of fluid into said reservoir from either of said passages, means providing for a restricted flow of fluid between opposite sides of said pump, and resilient means interposed directly between said valves and normally retaining both of said valves open, said resilient means and valves being constructed and arranged to provide for closure of the valve between the passage at the discharge side of said pump to hold open the other valve when said pump is operating, and to permit

closure of both of said valves in response to fluid flow resulting from the application of mechanical forces to said hydraulic device in a direction causing greater output flow than input flow while said pump is idle.

14. Structure as defined in claim 13 in which the valve controlling flow from the passage connected to the side of the hydraulic device requiring the larger flow is provided with abutment means locating said valve in open position relatively widely separated from its seat as compared to the other valve.

15. In a power unit of the character described, a pair of passages connected between opposite sides of a reversible pump and opposite ends of a power cylinder including a piston and piston rod, a transverse passage terminating at each end in an enlarged valve chamber, a reservoir in communication with said transverse passage intermediate its ends, a valve seat at the inner end of each chamber, each of said chambers being in communication with one of said pair of passages, a valve in each of said chambers, a plug closing the outer end of each chamber including an abutment portion engageable by the valve in said chamber to limit movement of said valve away from its seat, a compression spring in said transverse passage engaging both of said valves and permitting closure of both of said valves at different chamber pressures, the valve in the chamber communicating with the passage connecting said pump to the end of said cylinder remote from said piston rod being spaced further from its seat in open position than said other valve, and means independent of said aforementioned passages providing for a restricted flow of fluid between opposite sides of said pump.

16. A self-locking power unit comprising a hydraulic device having a differential input and output flow, a reversible pump for supplying fluid to said device, passages connecting opposite sides of said pump to opposite sides of said device, a fluid reservoir in communication with both of said passages, check valves controlling flow of fluid into said reservoir from either of said passages, means providing for a restricted flow of fluid between opposite sides of said pump, and resilient means normally retaining both of said valves open, said valves including means constructed and arranged to provide for simultaneous closure thereof to block movement of said hydraulic device by the application of external mechanical force in one direction when said pump is idle, but permitting reverse movement of said hydraulic device by external force with said pump idle.
